UNITED STATES PATENT OFFICE.

THEODORE G. LEWIS, OF BUFFALO, NEW YORK, ASSIGNOR TO BUFFALO DENTAL MANUFACTURING COMPANY, OF BUFFALO, NEW YORK, A CORPORATION OF NEW YORK.

DESIGN FOR A DENTAL BOX-FLASK.

52,826.

Specification for Design.

Patented Dec. 31, 1918.

Application filed September 6, 1918. Serial No. 252,979. Term of patent 7 years.

To all whom it may concern:

Be it known that I, THEODORE G. LEWIS, a citizen of the United States, residing at Buffalo, in the county of Erie and State of New York, have invented a new, original, and ornamental Design for Dental Box-Flasks, of which the following is a specification, reference being had to the accompanying drawing, forming part thereof.

The drawing is a perspective view of the dental box flask.

I claim:

The ornamental design for a dental box flask, as shown.

THEODORE G. LEWIS.
